Primary Examiner — Selina Sikder(74) *Attorney, Agent, or Firm* — Knobbe, Martens, Olson & Bear, LLP(57) **CLAIM**

The ornamental design for a chassis for an electronic irrigation controller, as shown and described.

DESCRIPTION

FIG. 1 is a front perspective view of a chassis for an electronic irrigation controller showing our new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left-side elevational view thereof; and,
 FIG. 7 is a right-side elevational view thereof.

Broken lines throughout the drawings indicate environmental elements that form no part of the claimed design.
